UNITED STATES PATENT OFFICE.

CHARLES P. DOUTNEY, OF BURLINGTON, VERMONT.

FIRE-EXTINGUISHING COMPOUND.

SPECIFICATION forming part of Letters Patent No. 625,293, dated May 16, 1899.

Application filed May 25, 1898. Serial No. 681,722. (No specimens.)

To all whom it may concern:

Be it known that I, CHARLES P. DOUTNEY, a citizen of the United States, residing in Burlington, in the county of Chittenden, State of Vermont, have invented a certain new and useful Improvement in Fire-Extinguishers; and I do hereby declare the following to be a full, clear, and exact specification of the same.

The object of my invention is to provide a cheap, practical, and efficient extinguisher for extinguishing fires and to compound same of ingredients which will be entirely harmless to human beings.

In carrying my invention into effect I take of bicarbonate of soda three parts, by weight, and of fullers' earth one part and mix the two together with sufficient yellow and red ochre to give the resulting compound a light brick-red color. My fire-extinguisher when thus compounded may be packed in suitable metallic or other vessels of convenient form for storage, shipping, and general use, and for this purpose I have found that cylinders constructed of tin or similar material are very convenient, and these cylinders may be provided with a hook by which they may be suspended upon the walls of a dwelling-house, factory, or office-building, in exposed and accessible places, so that when a fire occurs the extinguishers will be at hand and ready for instant use.

In using my improved fire-extinguisher all that is necessary to be done is to remove the

top from the canister or other receptacle in which it is stored and throw the extinguisher upon the fire. The action of the fire upon the compound results in its decomposition and the production of carbonic-acid gas, which, as is well known, prevents combustion and extinguishes fire.

I have found by experiment that if I employ bicarbonate of soda alone, throwing same upon the fire, it produces very little effect in extinguishing the flames. The addition of fullers' earth, however, I find effectively spreads the bicarbonate of soda among the flames, producing the same effect upon the flames as if they were smothered with a wet blanket. The addition of fullers' earth also prevents the bicarbonate of soda from caking, so that my fire-extinguisher will always be in condition for immediate use and will at all times retain its powdered form.

Having now described my invention, what I claim as new, and desire to secure by Letters Patent, is—

A fire-extinguisher consisting of bicarbonate of soda and fullers' earth, substantially in the proportions specified.

In witness whereof I have hereunto set my hand in presence of two witnesses.

CHARLES P. DOUTNEY.

Witnesses:

H. L. BEIL,
OTTO MUNK.
